INVENTOR,
Joseph D. Bee

UNITED STATES PATENT OFFICE

2,326,196

CONVERTIBLE BED

Joseph D. Bell, San Francisco, Calif.

Application August 28, 1940, Serial No. 354,467

11 Claims.

(Cl. 5—47)

The present invention relates to improvements in a convertible bed, and its principal object is to provide a bed that may be readily converted into a chair, and also into a lounge, which expression is used to indicate a rest intermediate a bed and a chair.

More particularly, it is proposed to provide a convertible bed of the character described in which all the changes may be made without changing the position of a rear supporting-member, which latter therefor, may be placed close to a wall, without making it necessary to move the device as a whole for effecting any desired change.

It is further proposed to provide, in a convertible bed of the character described, an L-shaped frame which has run-ways lying on the floor to serve as a track for a portion of the structure, and which has a back adapted to serve as a support for a mattress when arranged in bed position, with a superstructure rising from the back to serve as a head piece for the bed.

A further object of my invention is to provide a convertible bed that is economical of space, is decorative in appearance, makes the room appear larger when moved into seat or semi-reclining position, gives a fuller view of the rug, allows twin beds to be used, where ordinarily there would only be room for one bed, and in which all operating parts are concealed.

And finally it is proposed to provide a convertible bed that may be operated with the greatest of ease, yielding to a slight touch of the human hand for effecting desired changes.

Further objects and advantages of my invention will appear as the specification proceeds and the novel features of my new convertible bed will be fully pointed out in the claims hereto appended.

The preferred forms are illustrated in the accompanying drawings, forming part of this specification, in which:

Figure 1 shows a side elevation of one form of my convertible bed in bed position;

Figure 2, a side elevation of the same bed in semi-reclining position;

Figure 3, a side elevation of the same bed in chair position;

Figure 4, a fragmentary perspective view of a rear edge portion of my convertible bed, with the upholstery omitted.

While I have shown only the preferred forms of my invention, I wish to have it understood that various changes or modifications may be made within the scope of the claims hereto ap-

pended, without departing from the spirit of my invention.

Referring to the drawings in detail, and particularly to the form shown in the Figures 1 to 4, inclusive, my convertible bed 1 comprises in its principal features, a supporting frame 2, a mattress 3 and an operating mechanism whereby the mattress is supported with respect to the frame with freedom of various adjustments to be described hereafter.

The frame 2, when viewed in side elevation, may be described as being L-shaped, and comprises two horizontal run-ways or wear plates 4, arranged in parallel relation to lie on the floor surface, so as to form a track, and uprights 5 rising from the rear of the run-way and supporting a back member, indicated at 6, which serves as a spacing member for the run-ways 4, another spacing member being provided near the front, as indicated at 7.

The front edges of the run-ways are tapered toward the floor, as indicated at 8. The back member 6 has a head piece 9 rising therefrom, the head piece being suitably secured to the back member 6, as by rivets 10 and leaving the upper edge 11 of the back member free to serve as a support for the mattress when the latter is in bed position, as indicated in Figure 1.

The head piece in this position projects above the mattress and serves as a means for holding the pillow in place, as in conventional bed structure.

The mattress 3, which is intended to be full length for bed size, that is about six feet, is made in two sections 12 and 13 hinged together, as at 14, and covered by a suitable upholstery 15 to form an absolutely flat sleeping surface when the frame sections 12 and 13 are aligned, as shown in Figure 1.

The frame sections, however, which are rigid and preferably made of wood, may be swung on the hinge 14, into any desired angularity, as shown in Figures 2 and 3.

When in chair position, as indicated in Figure 3, the mattress 3 is supported by means of a pair of legs 16 projecting downwardly from the front edge of the seat, and provided with large rollers 17 adapted to roll on the floor surface in front of the run-ways 4.

In the same position, the rear section of the mattress is supported by means of two pairs of links, indicated at 18 and 19. These two pairs of links are supported on horizontal pivots 20 and 21 carried by horizontal brackets 22 secured to the rear ends of the run-ways and are attached

to the back section by means of brackets 23 through pivots 24 and 25.

The links of each pair are interconnected by cross-rods 26 and 27, and these cross-rods are connected to a rear bracket 28 by means of springs 29 and 30 which tend to pull the two pairs of links rearwardly from a forward position.

It will be noted that in Figure 3, the two pairs of links are arranged one rearward of the other, and that they run substantially parallel.

When the back is pushed forward to the position of Figure 2, by means of a forward push on the upper edge of the back, the rollers 17 roll forward, guiding the front edge of the seat section, and the pivots 24 and 25 at the upper ends of the links also move forward, at the same time carrying out a turning movement about each other, which causes the links 19 to partly cross the links 18, as shown in Figure 2 and which places the springs 29 and 30 under tension.

The rear portion of the seat of the mattress frame is provided with short legs 31 carrying rollers 32 which strike the run-ways when the position of Figure 2 has been reached and thus serve to support the hinge sections of the mattress in the intermediate or lounging position of Figure 2.

It will be noted that, during the movement of the mattress from the chair position of Figure 3 to the semi-inclined, or lounging position of Figure 2, the mattress advances considerably, while the L-shaped frame retains its position.

The back section of the mattress crosses the vertical planes passing through the pivots 20 and 21 while substantially retaining its upright position, but changes its angularity toward the end of the movement, as shown in Figure 2. In this position, the mattress is fairly well balanced between the front legs and the rear supports 24 and 25, so that the legs 31 rest very lightly on the run-ways when the chair is unoccupied. When weight is applied by an occupant, the legs 31, of course, serve to firmly support the rear edge of the seat 12.

But without weight, the mattress is so well balanced that a slight pressure on the upper end of the back section in a downward direction will raise the hinge, with its supporting legs 31, and cause the two mattress sections to assume a position of approximate alinement, but with a slight general upward slant from front to rear, since the two links 18 and 19 furnish a higher support than the front legs 16. If a person should sit down on the mattress in that position, the mattress would automatically fall back into the position of Figure 2.

For supporting the mattress in full bed position, as indicated in Figure 1, I provide two special pairs of legs 33 and 34, each of the same being provided with a caster 35. The front legs are pivoted underneath the front end of the seat section, as shown at 36, and are provided with a bell crank lever connection 37 having a transverse connecting rod 38, by means of which the front legs may be moved from the inclined position of Figure 2 to the vertical position of Figure 1.

The horizontal rod 38 is preferably formed with a crank or handle 39 for facilitating the manipulation thereof. The rear legs 34 are pivoted to the rear end of the seat section by means of cross-pins 40 supported in the fixed legs 31, the pins also serving as supports for the rollers 32, and they have extensions 41 connected to the front legs by means of links 42. Thus, when the

front legs are swung backward, the rear legs are swung forward, as shown in Figure 2, and when the front legs are swung forward into vertical position, the rear legs are swung backwards into vertical position, as shown in Figure 1.

Since the legs 33 and 34 are longer than the legs 16 and 31, the latter will be lifted bodily with the seat section of the mattress, and the seat section itself will be raised so that its bottom is in the plane of the upper edge of the back member 6, the legs 33 and 34 being dimensioned to produce this effect.

The hinge 14, of course, rises with the seat section, and causes the back section to execute what little further rocking movement is necessary for alining the back section with the seat section.

The links 18 and 19 are dimensioned and positioned to cause the extreme end of the back section to register with the back member 6 when it comes to rest thereon, as indicated in Figure 1.

My convertible bed is operated as follows:

Beginning with the position of Figure 3, to change to the position of Figure 2, it is only necessary to exert slight forward pressure on the upper end of the back. This normally causes the parts to assume the position of Figure 2, the legs 16 riding forwardly and the links 18 and 19 swinging forwardly, the latter crossing the former, as indicated. The legs 31 may either clear or lightly rest on the run-ways 4, but are ready to support any weight added by an occupant seating himself.

To move from the position of Figure 2 to that of Figure 1, slight downward pressure is brought to bear on the upper end of the back section of the mattress, which causes the pivots 24 and 25 to execute further turning movement about one another, and causes the legs 16 to advance slightly further, while the hinge 14 is raised to bring the two mattress sections into an approximate state of alinement in an inclined plane. The operator now grasps the handle 39 and pulls upwardly, whereby the legs 33 and 34 are swung into vertical position, and the seat is raised into horizontal position, while the back moves into alinement with the seat and comes to rest, at its rear end, on the back-member 6.

If it is desired to change from the position of Figure 3 to that of Figure 1 without staying in the intermediate position, the alinement of the two mattress sections may be carried out in a single movement by exerting forward pressure on the upper end of the back, followed by a slight downward pressure. The operation is completed by raising the handle 39 in the manner previously described.

For reversing the operation, the handle 39 is depressed from the position of Figure 1 for collapsing the legs 33 and 34 and the positions of Figure 2 and Figure 3 may be readily obtained by pushing backward on the front edge of the seat.

It should be observed, particularly by reference to Figure 4, that all the operating parts are confined within the outer margin of the mattress frame, which latter corresponds substantially to the outer margin of the supporting frame. This allows the mattress to be covered with sheets and blankets in the conventional manner, and allows the entire assembly to be covered by a bed spread provided with sides and ends completely enclosing the operating mechanism of the convertible bed. In commercial use, the head piece 9 could be upholstered and covered with mate-

rial matching the bed spread or interior decorations.

My convertible bed is intended for general use in all types of bed rooms in dwellings, apartment houses and hotels, but it is also particularly adapted for use in auto camps and the so-called station wagon type of motor vehicles where it has been installed without requiring any modification or installation expense.

I claim:

1. In a convertible bed, an L frame comprising a horizontal wear plate and a rear vertical member, a mattress frame comprising a front section and a rear section hinged together for movement between bed and chair positions, means for supporting the mattress frame over the wear plate with freedom of movement substantially in chair position from a point over the rear of the wear plate in a forward direction, and means cooperable with the forward end of the wear plate for arresting the movement of the mattress frame, the mattress supporting means being operable to guide the mattress from advanced chair position to bed position with one end of the frame resting on the vertical member.

2. In a convertible bed, a frame comprising a horizontal wear plate, a back rest, means for supporting the back rest over the wear plate with freedom of movement from an upright position over the rear end of the wear plate to a substantially upright position over the front end of the wear plate, and means cooperable with the front end of the wear plate for arresting the said movement, the back rest supporting means being operable to guide the back rest from its advanced upright position into horizontal position for use as a bed.

3. In a convertible bed, an L frame comprising a horizontal wear plate, a rear vertical member and a head piece rising from the vertical member and forming an off-set therewith, a mattress frame comprising a front section and a rear section hinged together for movement between bed and chair positions, means for supporting the mattress frame over the wear plate with freedom of movement substantially in chair position from a point adjacent the rear vertical member in a forward direction, and means cooperable with the front end of the wear plate for arresting the forward movement of the mattress frame, the mattress frame supporting means being operable to guide the mattress from advanced chair position to bed position with the rear end of the mattress frame resting on the offset and the end face up against the head piece.

4. In a convertible bed, an L frame comprising a horizontal track member and a vertical head member, a mattress frame comprising two sections, one a back section and the other a seat section, hinged together with freedom of movement between bed and chair positions, means for supporting the mattress frame in chair position comprising a leg for supporting the front edge of the seat section and two pairs of links carried by the track member and supporting the back section in upright position adjacent the head member, the links being operable to guide the back section forward on an arc and in upright position to a predetermined point on the down grade of the arc, and to then rock the same toward horizontal position, and a relatively short leg projecting from the rear edge of the seat section over the track so as to strike the latter and

give support to the hinge connection when the back has reached said predetermined position.

5. In a convertible bed, an L-frame comprising a horizontal track, a rear vertical member and a head piece rising from the vertical member and forming an off-set therewith, a mattress frame comprising two sections, one a back section and the other a seat section, hinged together with freedom of movement between bed and chair positions, means for supporting the mattress frame in chair position comprising a leg for supporting the front edge of the seat section and two pairs of links carried by the track and supporting the back section in upright position adjacent the head member, the links being operable to guide the back section forward on an arc and in upright position to a predetermined point on the down grade of the arc and to then rock the same toward horizontal position, and a relatively short leg projecting from the rear edge of the seat section over the track so as to strike the latter and to give support to the hinge connection when the back has reached said predetermined point, the links being operable to position the rear end of the mattress frame on the off-set with the rear face thereof up against the head piece, and the latter being sufficiently high to form a cushion-retaining abutment for the horizontal mattress frame.

6. In a convertible bed, an L-frame comprising a horizontal member and a vertical head member, a mattress frame comprising two sections, one a back section and the other a seat section, hinged together with freedom of movement between bed and chair positions, means for supporting the mattress frame in chair position comprising a leg carried by the seat for supporting the front edge of the seat section and means carried by the horizontal member forwardly of the head member for supporting the back section adjacent the head member, the latter means being operable to guide the mattress frame forward substantially in chair position to a predetermined point of advance and to then rock the back section into approximately horizontal position with one end of the back section adjacent the head member and movable means carried by the seat section operable to lift the seat into a position of alignment with the horizontal back section.

7. In a convertible bed, an L-frame comprising a horizontal member and a vertical head member, a mattress frame comprising two sections, one a back section and the other a seat section, hinged together with freedom of movement between bed and chair positions, means for supporting the mattress frame in chair position comprising a leg carried by the seat for supporting the front edge of the seat section and means carried by the horizontal member substantially midway of the length thereof for supporting the back section adjacent the head member, the latter means being operable to guide the mattress section forward substantially in chair position to a point where the hinge is spaced from the head rest substantially by the length of the back section and to rock the back rest thereafter into approximately horizontal position with one end of the back section adjacent the head member, the latter having an off-set for supporting the free end of the back section in the latter position and the seat having means operable to lift the seat into a position of alignment with the horizontal back.

8. In a convertible bed, an L-frame comprising

ing a horizontal member and a vertical head member, a mattress frame comprising a back section and a seat section hinged together with freedom of movement between chair and bed positions, and means for supporting the mattress frame substantially in chair position forwardly of and with its hinge spaced from the head member substantially by the length of the back section, comprising a leg carried by the seat and supporting the front of the seat section, a leg supporting the rear of the seat and resting on the horizontal member and supporting means for the back section positioned forwardly of the head member, the latter means being operable to guide the mattress in chair position toward the head member when the seat section is pushed toward that member and to guide the mattress into bed position when the rear end of the seat is lifted, and means for lifting said rear end.

9. In a convertible bed, a main frame having a horizontal member, a mattress frame comprising a seat section and a back section hinged together with freedom of movement between angular and alined positions, a front leg supporting the front edge of the seat section, a rear leg resting on the horizontal member and supporting an intermediate section of the mattress frame, means carried by the horizontal member for supporting the back section in upwardly inclined position, and means carried by the seat operable for bodily lifting the seat to raised horizontal position directly above the former position including means for supporting the seat in said raised position, the back-supporting means being operable to swing the back into a position of hor-

izontal alinement with the seat when the latter is raised.

10. In a convertible bed, a main frame having a horizontal member, a mattress frame comprising a seat section and a back section hinged together with freedom of movement between angular and alined positions, a front leg supporting the front edge of the seat, a rear leg shorter than the front leg supporting the rear edge of the seat and having support on the horizontal member, the two legs supporting the seat in rearwardly declining position, a pair of links carried by the horizontal member and supporting the back in inclined position with freedom of rocking movement, and means carried by the seat operable for bodily lifting the seat to raised horizontal position directly above its former position including means for supporting the seat in said raised position, the back-supporting means being operable to aline the back and the seat when the latter is raised.

11. In a convertible bed, a mattress frame comprising a seat section and a back section hinged together with freedom of movement between chair and bed positions, means for supporting the mattress in bed position comprising a leg supporting the front of the seat, a leg supporting the rear of the seat and rockable means for supporting the back section, means for collapsing the two legs whereby the seat is lowered and the back section is rocked into inclined position, and means for stopping the downward movement of the seat when the mattress reaches a lounge position.

JOSEPH D. BELL.
